UNITED STATES PATENT OFFICE.

GEORGE H. CLARK, OF BROOKLYN, NEW YORK, ASSIGNOR TO RADIO CORPORATION OF AMERICA, A CORPORATION OF DELAWARE.

RADIO SIGNALING SYSTEM.

Application filed April 26, 1921. Serial No. 464,555.

To all whom it may concern:

Be it known that I, GEORGE H. CLARK, a citizen of the United States, and a resident of Brooklyn, New York, have invented certain new and useful Improvements in Radio Signaling Systems, of which the following is a specification accompanied by drawings.

The present invention relates to improvements in radio signaling with continuous waves. As is well known, high frequency continuous waves or oscillations are incapable of audible reception without special means utilized either at the transmission station or at the receiving station.

In case that the waves are modulated at an audible rate at the transmitting station no special means are necessary at the receiving station for detection and any receiving set equipped for detection of damped waves will detect the modulated continuous waves. In modulating the wave at the transmission station it is usual to superimpose an E. M. F. of low frequency on the main E. M. F. in the antenna or to change the constants in the antenna at an audible rate in order to produce the modulation.

Instead of thus changing the constants of the antenna or adding currents from another source I periodically absorb at an audible rate portions of the signal waves so that the same do not get in the antenna. Thus the signal current is in effect interrupted at an audible rate by the absorption in a non-radiating circuit of portions of the generated oscillations. In my copending application Serial No. 452,895, filed March 17, 1921, I have disclosed an arrangement operating in the manner set forth. In accordance with the present invention I utilize a somewhat similar method, but utilize in conjunction therewith different means and methods which I have discovered for diverting the oscillations to either the antenna or the absorption circuit.

In my previous application I have specifically described an arrangement embodying an absorption circuit comprising inductance, capacity and resistance. To divert the oscillations from the antenna to the absorption circuit the resistance is short circuited

which does not substantially affect the tuning of the absorption circuit.

I have found that the oscillations may also be diverted to either the antenna or the absorption circuit by slight changes in the tuning of the absorption circuit, without necessarily substantially altering the resistance. I have also found that the absorption circuit functions much better when adjusted to a wave length much shorter than the main wave length. When the constants are adjusted to a wave length of about one-third the main wave length a slight variation of the inductance or capacity is sufficient to divert the oscillations from the absorption circuit to the antenna or vice versa. These discoveries are utilized in the present invention in a manner which will be set forth more fully hereafter.

While my invention is applicable to various types of high frequency continuous wave generating systems, it is described in connection with an arc converter system which has the non-radiating absorption circuit for producing the signal. In the embodiments of the invention herein described the current is periodically absorbed in the absorption circuit by varying the tuning of the absorption circuit at an audible rate and a telegraph key sends substantially all of the oscillations into either the absorption circuit or the antenna when the key is open and in the closed position, working in conjunction with modulating or periodically absorbing means sends the oscillations alternately into the antenna and oscillation circuit at an audible rate.

One object of my invention is to divert the oscillations from the antenna to the absorption circuit or vice versa by varying the tuning of the absorption circuit.

Another object of my invention is to divert the oscillations at an audible rate during signaling to produce signals which can be received without special means.

Further objects of the invention will appear in the following description of several embodiments of my invention which are illustrated in the drawing in which:

Fig. 1 is a diagrammatic representation

of an arrangement embodying the invention as applied to an arc converter in which signaling and modulation are both produced by varying the tuning of the absorption circuit.

5 Figs. 2 and 3 are diagrammatic representations of modifications.

In the drawings, 1 is an arc fed by a generator 2 and having a field coil 3 to provide the field for influencing the arc in the well known way. The antenna 4 is connected to the upper electrode through the adjustable loading coil 5 and the lower electrode is connected to the ground at 6. In

10 Fig. 1 the absorption circuit comprises capacity 7 and inductance, the latter comprising coil 8 with adjustable contact and an additional inductance 9 of small value adapted to be readily cut into or out of the absorption circuit in a manner which will be further described. In the modification of Fig. 1 the absorption circuit contains no special resistance and the signaling as well as the modulation is produced by detuning.

15 For modulation a contact arm 10 is moved back and forth on the turn 9 of inductance to cut this in and out of the circuit at a rate corresponding to an audible note. There are, of course, many ways of doing this mechanically, but in the drawing I have shown a cam 11 rotated by a motor 12, which acts on a pivoted lever 13 which is integral with contact arm 10. The cam is preferably shaped so that no movement of the contact arm is produced during a considerable portion of each revolution and the tuning will therefore remain constant during this period. A signaling key 14 is connected across the inductance 9 so that in the raised position it short circuits the inductance 9 and when depressed for telegraph signaling it opens the short circuit around the inductance.

20 With the arrangement described all of the oscillations will be sent into either the absorption circuit or the antenna as desired when the telegraph key is up. This will depend upon whether the absorbing condition of the absorption circuit is adjusted to occur when inductance 9 is in circuit or when the latter is short circuited. Signaling may be effected in either condition.

25 However, if we consider the circuit to be non-absorbing when the inductance 9 is short circuited, the operation will be as follows: When the key 14 is up and no signals are being sent, the oscillations favor the antenna to the practical exclusion of the absorbing circuit and the former will thus radiate continuous unmodulated waves which however cannot be detected without special means at the receiving station. This condition will exist regardless of the operation of the contact arm 10 which operates in conjunction with the inductance 9 and

during such periods the operation of the modulating mechanism described has no effect on the character of the radiation. When the key is operated to produce telegraphic signals, the short circuit on the inductance 9 is removed during the signaling interval and the oscillations will be diverted alternately to the absorption circuit and the antenna in accordance with the position of the contact arm. When the point 15 of the cam is in contact with the lever 13, the inductance 9 is cut into the absorbing circuit and substantially all of the oscillations are diverted from the antenna circuit. When the cam rotates 180° so that point 16 is in contact with the lever the inductance 9 is short circuited by the contact arm 10, thus disturbing the absorbing condition of the absorption circuit and causing the oscillations to return to the antenna circuit. This alternation of the oscillations between the two circuits occurs at tone frequency, and the resulting groups of oscillations impressed on the antenna during the period when the key is operated which correspond to dots and dashes will occur in groups of oscillations having an audible group frequency which can be detected without using any special means at the receiving station.

30 Obviously the tuning can be varied and signaling produced in the same way as described by cutting capacity in and out of the absorbing circuit at an audible rate.

35 It will also be obvious that by selecting the constants of the absorbing circuit of such values that the oscillations favor the absorption circuit when the signaling key is up, I am able to prevent radiation except when signals are being sent, during which periods the oscillations alternately favor the antenna and the absorption circuit in the same manner as heretofore described.

40 In either case in accordance with the embodiment described modulation is produced by changing the tuning of the absorption circuit at an audible rate and signaling is also produced by changing the tuning.

45 In accordance with the modifications of Figs. 2 and 3 radiation of the same character as described in connection with Fig. 1 is secured, but signaling is done without having the movements of the key affect the tuning of the absorption circuit.

50 Fig. 2 shows an arrangement in which the absorbing circuit is detuned by varying the capacity. A condenser 17 of small value comprising the plate 18 rotated by a motor at an audible rate is utilized to detune the absorption circuit and alternately send the oscillations into the antenna and absorbing circuit to give tone characteristics. Such an arrangement is illustrative of the use of a condenser instead of the inductance 9 of Fig. 1 for detuning the absorption circuit. It is

sometimes convenient to utilize a resistance in the absorption circuit in conjunction with the signaling key. This is shown in Figs. 2 and 3. In Fig. 2 the resistance 19 is normally in circuit and continuous unmodulated oscillations are impressed on the antenna circuit except during signaling when this is short circuited by key 14 and the oscillations are then periodically absorbed 10 by the absorption circuit at an audible rate due to the periodical detuning of the absorption circuit by the rotating condenser.

Fig. 3 shows an arrangement in which the resistance 18 is short circuited for signaling 15 by means of the telegraph key as in Fig. 2 and the inductance is varied as in Fig. 1 to produce detuning. The periodically variable inductance comprises a pair of flat coils 20, 21 and a conducting shield 22 movable into and out of the space between the coils to vary the inductance. The periodic movement of the shield through the field between the coils at an audible rate is secured 20 by means of a rotating cam 23 acting on a lever 24 for example.

In each of the modifications described it 25 will be understood that the absorbing circuit constants are preferably such that the tuning corresponds to a wave length considerably less, and usually about one-third the main wave length, as I have found that the oscillations may be more readily diverted by mistuning than when the absorbing circuit is adjusted to the main wave length.

Having described my invention, what I 30 claim is:

1. The method of signaling which comprises generating high frequency oscillations, supplying the energy thereof alternately to two tuned circuits, radiating signal waves from one thereof, absorbing energy in the other thereof, and controlling the alternation therebetween by mechanical variation of the impedance elements at an 40 audio rate.

2. The method of signaling which comprises generating high frequency oscillations, feeding said oscillations alternately to two tuned circuits, radiating signal waves 45 from one thereof, absorbing energy in the other thereof, and controlling the alternation therebetween by moving portions of the impedance elements in the absorbing circuit at an audible rate.

3. The method of signaling which comprises generating high frequency oscillations, feeding said oscillations alternately to two tuned circuits, radiating signal waves from one thereof, absorbing energy in the other thereof, and controlling the alternation therebetween by moving a portion of the impedance elements in the absorbing circuit at an audible rate, and by shunting impedance elements in the same circuit at a signal 55 code rate.

4. A radio signaling system comprising a source of energy, a converter for producing high frequency electrical oscillations, an antenna circuit connected thereto, a tuned absorbing circuit also connected thereto, impedance means included in said absorbing circuit and power actuated means for moving portions thereof at an audible frequency rate whereby the impedance thereof is varied and the oscillations caused to alternate between said antenna and said circuit.

5. A radio signaling system comprising a source of energy, a converter for producing high frequency electrical oscillations, an antenna circuit connected thereto, a tuned absorbing circuit also connected thereto, impedance means included in said absorbing circuit, power actuated means for moving portions thereof at an audible frequency rate, whereby the impedance thereof is varied and the oscillations caused to alternate between said antenna and said circuit, and a keying means cooperating with said circuit to shunt an impedance whereby said alternation is suspended during non-signaling periods.

6. In a radio signaling system, the combination of an antenna, a generator of continuous oscillations, an absorption circuit, a resistance in said circuit adapted to damp oscillations out of the absorption circuit, signaling means adapted to intermittently short circuit said resistance, tuning means for said absorption circuit, and means for periodically changing the effective values 100 of the constants of said tuning means at an audible rate.

7. In a radio signaling system, the combination of an antenna, a generator of continuous oscillations, an absorption circuit, a resistance in said circuit adapted to damp oscillations out of the absorption circuit, signaling means adapted to intermittently short circuit said resistance, an inductance for tuning said absorption circuit, and means 110 for periodically changing the effective tuning inductance at an audible rate.

8. In radio signaling systems, the combination of an antenna, an arc generator of continuous oscillations for energizing said antenna, an absorption circuit bridged across said arc generator for absorbing oscillations produced thereby, said absorption circuit having its constants so chosen as to have a predetermined resonance characteristic and to be resonant at a wave length substantially less than the wave length of the oscillations radiated, and means for periodically varying one of the constants of said absorbing circuit between predetermined fixed values at an audible rate to periodically modify said resonance characteristic, whereby a characteristic tone is impressed on the radiated oscillations.

9. In radio signaling systems, the combi-

nation of an antenna, an arc generator of continuous oscillations for energizing said antenna, an absorption circuit bridged across said arc generator for absorbing oscillations produced thereby, said absorption circuit having its constants so chosen as to give a predetermined resonance characteristic and to be resonant at a wave length substantially one-third of that of the oscillations.

tions radiated, and means for periodically varying one of the constants of said absorbing circuit between predetermined fixed values at an audible rate, whereby a characteristic tone is impressed upon the radiated oscillations.

In testimony whereof I have hereunto affixed my signature.

GEORGE H. CLARK.
